(57) **CLAIM**

The ornamental design for a barrel massage roller, as shown and described.

DESCRIPTION

FIG. 1 is a front perspective view of a first embodiment of the present invention;

FIG. 2 is a front elevation view of the embodiment shown in FIG. 1;

FIG. 3 is a rear elevation view of the embodiment shown in FIG. 1;

FIG. 4 is a right side view of the embodiment as shown in FIG. 1;

FIG. 5 is a left side view of the embodiment as shown in FIG. 1;

FIG. 6 is a top view of the embodiment as shown in FIG. 1;

FIG. 7 is a bottom view of the embodiment as shown in FIG. 1;

FIG. 8 is an enlarged perspective view of the embodiment shown in FIG. 1;

FIG. 9 is a front perspective view of a second embodiment of the present invention;

FIG. 10 is a front elevation view of the embodiment shown in FIG. 9;

FIG. 11 is a rear elevation view of the embodiment shown in FIG. 9;

FIG. 12 is a right side view of the embodiment shown in FIG. 9;

FIG. 13 is a left side view of the embodiment shown in FIG. 9;

FIG. 14 is a top view of the embodiment shown in FIG. 9;

FIG. 15 is a bottom view of the embodiment shown in FIG. 9; and,

FIG. 16 is an enlarged perspective view of the embodiment shown in FIG. 9.

The broken lines in the drawings are for the purpose of illustrating portions of the barrel massage roller which form no part of the claimed design.

1 Claim, 14 Drawing Sheets
